UNITED STATES PATENT OFFICE.

HARVEY B. MORSE, OF PORTLAND, MAINE, ASSIGNOR TO MORSE MANUFACTURING COMPANY, OF PORTLAND, MAINE, A CORPORATION OF MAINE.

DRAWER-SUPPORT.

No. 917,885.

Specification of Letters Patent.

Patented April 13, 1909.

Application filed June 20, 1908. Serial No. 439,506.

To all whom it may concern:

Be it known that I, HARVEY B. MORSE, a citizen of the United States, and resident of Portland, in the county of Cumberland and State of Maine, have invented new and useful Improvements in Drawer-Supports, of which the following is a specification.

This invention relates to improvements in drawers.

10 It is designed for use in furniture, wall cases, etc.

It is designed to provide a drawer which can be readily removed entirely from the case or which can be drawn out a greater or 15 less distance from the case and remain suspended.

It is also designed to provide means whereby the drawer can be moved readily out and in and to so hang it that when pushed in it 20 will be automatically cushioned or retarded to prevent shock or jar when it is pushed away in.

In the drawings herewith accompanying and making part of this application, Figure 25 1 is a side elevation of a two drawer case showing my drawer and its mounting therein, a portion of the side of the casing being removed, one drawer being shown withdrawn; and Fig. 2 is a transverse vertical 30 sectional view on line x—x of Fig. 1.

Same letters of reference refer to like parts.

In said drawing A is a suitable casing having a track B affixed thereto on either side of the drawer space. The drawer supporting device on either side consists of a double slide C—C' supported upon track B by means of hangers D—E attached to the sides of the slides. Hanger D has an anti-friction roll F, shown in dotted lines Fig. 1, adapted to travel against the lower edge of track B, and hanger E has an anti-friction roll G adapted to travel against the lower edge of the part C. Suspended from the 40 part C' by means of hangers I and J is another slide H, the hanger I being provided with an anti-friction roll K running against the lower edge of the part C' and an anti-friction roll L running against the under edge 45 of the slide H. The inner and outer ends of slide H are connected by stirrups M which extend across the space occupied by the drawer, see Fig. 2, and upon these stirrups the drawer N is loosely supported, the lower

edges of the drawer being provided with recesses O to give entrance to the stirrups. This construction admits of the drawer being lifted entirely from the stirrups whenever desired but serves to removably lock the drawer to the stirrups. Pulling out the 55 drawer pulls out the slides also. The track B is provided with a stop P which limits the outward movement of the double slide C—C' and a stop Q on the part C' limits the outward movement of the slide H. It will be 60 noted that when the drawer is withdrawn until the hanger I comes in contact with stop Q, the slide C—C' does not move on track B but when slide H is checked by the stop Q the slide C—C' moves on track B until 65 hanger B comes in contact with stop P which is the outward limit of the drawer. When the drawer is being pushed in at first all the parts travel on the anti-friction rolls but when about half way in the center of gravity 70 of the parts changes, the inner end of the double slide C—C' and the slide H tend to drop so that hangers D and I slide on the upper edges of track B and part C' respectively, the friction arising therefrom tending 75 to retard the drawer and prevent shock. The drawer is provided on either side with a lateral projection R forming a guide for the drawer and a space S between the drawer and casing for the track and drawer supporting 80 slides.

Having thus described my invention and its use I claim:

1. In a drawer support, the combination with a drawer casing having tracks affixed 90 thereto at opposite sides of the drawer space, of a double slide suspended from each of said tracks and movable thereon, a single slide suspended from each of the lower members of said double slides and movable thereon, the ends of said single slides being provided with stirrups, and a drawer supported in said stirrups.

2. In a drawer support, the combination with a drawer casing having tracks affixed 100 thereto at opposite sides of the drawer, of a double slide suspended from each of said tracks and movable thereon, a single slide suspended from each of the lower members of said double slides and movable thereon, the ends of said lower slides being provided with stirrups, and a drawer removably supported in said stirrups.

3. In a drawer support, the combination with a drawer casing having tracks affixed thereto at opposite sides of the drawer, of a double slide suspended from each of said tracks and movable thereon, a single slide suspended from each of the lower members of said double slides and movable thereon, the ends of said single slides being provided with stirrups, and a drawer having recesses 10 in the bottom to give entrance to said stirrups.

4. The combination with a drawer casing having tracks affixed thereto at opposite sides of the drawer space, of a drawer support comprising a double slide suspended from and movable upon each of said tracks and a single slide suspended from and movable upon the lower member of each of said double slides, the inner and outer ends of the 20 single slides being connected by drawer supporting stirrups extending across the drawer space, means for limiting the outward movement of the slides, and a drawer supported in said stirrups.

25 5. The combination with a drawer casing having tracks affixed thereto at opposite

sides of the drawer space, of a drawer support comprising a double slide suspended from and movable upon each of said tracks and a single slide suspended from and 30 movable upon the lower member of each of said double slides, the inner and outer ends of the single slides being connected with drawer supporting stirrups extending across the drawer space, hangers for suspending the double slides to the track, and hangers for suspending the single slides to the double slides, the hangers on the inner ends having frictional engagement with the top of the track and double slides respectively and anti-frictional engagement with the bottom of the track and double slide respectively.

In testimony whereof, I have signed my name to this specification in the presence of 45 two subscribing witnesses this 11th day of June, 1908.

HARVEY B. MORSE.

In presence of

ELGIN C. VERRILL,
MARION RICHARDS.
